(57) **CLAIM**

The ornamental design for an LED clock, as shown and described.

DESCRIPTION

FIG. 1 is a perspective view of an LED clock showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left, top perspective view thereof.

FIG. 9 is an enlarged detail view of area 9 shown in FIG. 1.

FIG. 10 is an enlarged detail view of area 10 shown in FIG. 3.

FIG. 11 is an enlarged detail view of area 11 shown in FIG. 6; and,

FIG. 12 is an enlarged detail view of area 12 shown in FIG. 8.

The broken lines in the drawings depict portions of the LED clock that form no part of the claimed design.
